ELECTRIC CIRCUIT

Albert Jan Brouwer, Hilversum, Netherlands, assignor to Hartford National Bank and Trust Company, Hartford, Conn., as trustee

Application April 12, 1950, Serial No. 155,454
In the Netherlands May 2, 1949

4 Claims. (Cl. 323—75)

1

This invention relates to circuits for deriving a voltage adjustable in value and polarity from a source of voltage, and more particularly to such circuits in which the mean momentary potential of the terminals between which the adjustable voltage is established is equal to the mean momentary potential at the terminals of the source of voltage.

Circuits of this kind are utilised for feeding a symmetrical load device, for example for supplying adjustable direct voltages to one pair of deflecting electrodes of a cathode ray tube. In order to permit adjustment of the position of the image spot, the direct voltage between the electrodes is required to be adjustable, while in view of distortion the mean potential of the two electrodes must remain independent of this adjustment.

In a known circuit of this kind the source of voltage is connected to the series-combination of a fixed resistance, an adjustable resistance and a second fixed resistance of the same value. The adjustable voltage is taken off between the two ends of the adjustable resistance. This gives rise to the disadvantage that in the case of constant polarity and value of the voltage of the source of supply, the adjustable voltage can be controlled from a maximum value to the value zero so that the polarity can never be inverted. This inversion may be achieved, however, by connecting the source of voltage in a suitable manner to two identical potentiometers which are coupled mechanically. On account of the requirement of symmetry, the potentiometers must, however, possess substantially identical characteristic curves, which can be realised only with difficulty and is in any case comparatively expensive.

The invention provides a novel circuit by which the aforesaid disadvantage is overcome.

In a preferred embodiment of the invention, a source of voltage supplies a Wheatstone bridge circuit in which, starting from a diagonal connected to the source of supply, one branch of the bridge includes the series-combination of ohmic resistances R_1 , R_2 , R_3 and the other branch of the bridge includes the series-combination of ohmic resistances R_3 , R_2 , R_1 , while the junction of R_2 and R_3 in one branch of the bridge is connected to that in the other branch by way of an adjustable resistance R_4 , the adjustable voltage being taken off between the junction of R_1 and R_2 in the two bridge branches and the resistance being so proportioned that the resistance value

$$\frac{2R_2R_3}{R_1 - R_2 - R_3}$$

2

lies within the region in which R_4 is adjustable. Other embodiments of the circuit according to the invention may be obtained by substituting for all the ohmic resistances impedances having the same phase angle and whose values satisfy the same relations as the ohmic resistances.

By this proportioning the polarity of the adjustable voltage in this circuit is found to be invertible by variation of R_4 or of the corresponding impedance with constant polarity of the voltage of the source of voltage, so that the control range of the adjustable voltage extends from a predetermined positive value to a predetermined negative value.

The invention will now be explained more fully by reference to the accompanying drawing wherein:

Fig. 1 is a schematic diagram of one preferred embodiment of the invention, and

Fig. 2 is a schematic diagram of a second preferred embodiment.

In Figure 1, reference numeral 1 indicates the source of voltage to which a bridge circuit is connected. The ohmic resistances R_1 , R_2 , R_3 are included in succession in series in the branch 2—3—4 of the bridge and the resistances R_3 , R_2 , R_1 are included in succession in series in the branch 2—5—4 of the bridge. An adjustable resistance R_4 is provided between the points 3 and 5. The adjustable voltage is taken from points 6 and 7 and supplied to terminals 8 and 9. The circuit exhibits symmetry, since point 7 is connected to the points 2 and 4 in a similar manner as point 6 is connected to the points 4 and 2. The mean potential of the points 6 and 7 is thus equal to that of the points 2 and 4. The voltage between 6 and 7 is adjustable by variation of the resistance R_4 . This voltage is found to be equal to

$$\frac{R_4(R_2 - R_1 + R_3) + 2R_2R_3}{R_4(R_2 + R_1 + R_3) + 2(R_1 + R_2)R_3} \cdot e \quad (1)$$

in which e represents the voltage between the points 2 and 4. With that resistance value R_{40} of R_4 at which

$$R_{40} = \frac{2R_2R_3}{R_1 - R_2 - R_3} \quad (2)$$

this voltage will become zero, as it follows from Equation 1. Upon a variation of R_4 by which the value R_{40} is passed, the polarity of the adjustable voltage with constant polarity of the voltage of the source of voltage will be inverted, as it also appears from Equation 1. Consequently, in order to permit variation of the polarity of the adjustable voltage, it must be ensured that

R_{40} lies within the control range of R_4 . This, of course, implies that R_{40} is positive, as it follows from Equation 2 that for this purpose $R_1 > R_2 + R_3$.

In most cases it is desirable that the adjustable voltage becomes as much positive as negative, that is, if the voltage of the source of voltage is constant, the absolute values of the adjustable voltage at the two boundaries of the control range are equal. If $R_{4 \text{ min}}$ and $R_{4 \text{ max}}$ represent the minimum and maximum values of R_4 , this is achieved if

$$\frac{R_{4 \text{ max}}(R_2 - R_1 + R_3) + 2R_2R_3}{R_{4 \text{ max}}(R_2 + R_1 + R_3) + 2(R_1 + R_2)R_3} = \frac{-R_{4 \text{ min}}(R_2 - R_1 + R_3) + 2R_2R_3}{R_{4 \text{ min}}(R_2 + R_1 + R_3) + 2(R_1 + R_2)R_3}$$

In one embodiment it was found that

$$R_1 = 6M\Omega$$

$$R_3 = 50k\Omega$$

$$R_2 = 2.5M\Omega$$

$$R_4 = 0 - 500k\Omega$$

R_4 was in this case an adjustable resistance having a logarithmic characteristic curve.

The symmetry of the circuit is only dependent upon the fixed resistances, while the characteristic curve of the adjustable resistance need not therefor satisfy predetermined requirements.

It is evident that R_4 may be replaced by any bipole which is active as an ohmic resistance and by which this resistance may be acted upon in some manner or other.

If, as is shown in Fig. 2, the source of voltage I is in the form of a carrier-wave generator and if R_4 is controlled in the rhythm of a signal from a source 10 in such manner that R_4 is exactly equal to R_{40} in the absence of the signal, a modulated voltage is set up at the terminals 8 and 9 in which the carrier wave is suppressed. The same result may be achieved with another circuit according to the invention which may be derived from the circuit above described by substituting all the ohmic resistances by impedances having the same phase angle. In the Equations 1 and 2 the resistance values R_1 , R_2 , R_3 and R_4 are required to be replaced by the values Z_1 , Z_2 , Z_3 , Z_4 of the corresponding impedances. Control of R_4 (Z_4) in accordance with the signal may be effected by conventional means such as a reactance tube.

What I claim is:

1. A circuit for deriving from a voltage source a voltage adjustable in value and polarity, the mean momentary potential at the terminals between which the adjustable voltage appears being invariably equal to the mean momentary potential at the terminals of the source, said cir-

cuit comprising a Wheatstone bridge having first and second branches connected in parallel to the terminals of the voltage source, the first branch being constituted by three serially connected impedances whose successive values starting from one end of the first branch is represented by Z_1 , Z_2 and Z_3 , the second branch being constituted by three serially connected impedances whose successive value starting from the corresponding end of the second branch is represented by Z_3 , Z_2 and Z_1 , a control impedance represented by Z_4 adjustable within a predetermined range and connected between the junction of impedances Z_2 and Z_3 in the first branch and the junction of impedances Z_3 and Z_2 in the second branch, and a pair of output terminals connected between the junction of impedances Z_1 and Z_2 in the first branch and the junction of Z_2 and Z_1 in the second branch, the impedances having relative values at which the resultant impedance

$$\frac{2Z_2Z_3}{Z_1 - Z_2 - Z_3}$$

25 lies with the range in which control impedance Z_4 is adjustable, impedances Z_1 , Z_2 , Z_3 and Z_4 having the same phase angle.

2. A circuit as claimed in claim 1, characterised in that the adjustable voltage established at the output terminals at the maximum possible value $Z_{4 \text{ max}}$ of impedance Z_4 for a constant polarity and value of the voltage of the voltage source has substantially the same absolute value as that occurring at the minimum possible value $Z_{4 \text{ min}}$ of impedance Z_4 in that the impedances are chosen to be such that the condition

$$\frac{Z_{4 \text{ max}}(Z_2 - Z_1 + Z_3) + 2Z_2Z_3}{Z_{4 \text{ max}}(Z_2 + Z_1 + Z_3) + 2(Z_1 + Z_2)Z_3} = \frac{-Z_{4 \text{ min}}(Z_2 - Z_1 + Z_3) + 2Z_2Z_3}{Z_{4 \text{ min}}(Z_2 + Z_1 + Z_3) + 2(Z_1 + Z_2)Z_3}$$

is substantially satisfied.

3. A circuit as claimed in claim 1, characterised in that the impedances are constituted by ohmic resistances.

4. A circuit, as set forth in claim 1, wherein said voltage source is constituted by a carrier wave generator and wherein said control impedance Z_4 is varied throughout its range in accordance with a modulation signal, whereby a suppressed carrier modulated wave is developed at said output terminals.
